UNITED STATES PATENT OFFICE

102,821

DESIGN FOR A TEXTILE FABRIC

Curt Erwin Forstmann, Montclair, N. J.

Application May 14, 1936, Serial No. 62,644

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing forming part thereof.

In the drawing, the sole figure of which is a plan view of a piece of the textile fabric embodying the design of the present invention, the cloth depicted is of a single color.

The design has three-dimensional characteristics. It has the appearance of parallel chains of broad woolly elevated nubs connected by narrow less elevated ridges crossed by a plurality of fine smooth finished stitches, the nubs of adjacent chains being staggered.

I claim:

The ornamental design for a textile fabric as described and as shown.

CURT ERWIN FORSTMANN.
